UNITED STATES PATENT OFFICE.

WILLIAM VIRGO WILSON, OF JUBILEE STREET, MILE END, COUNTY OF MIDDLESEX, ENGLAND.

PROCESS OF ORNAMENTING WALL AND OTHER PAPERS.

SPECIFICATION forming part of Letters Patent No. 340,026, dated April 13, 1886.

Application filed October 15, 1885. Serial No. 179,978. (No specimens.)

To all whom it may concern:

Be it known that I, WILLIAM VIRGO WILSON, a subject of the Queen of Great Britain, residing at Jubilee Street, Mile End, in the county of Middlesex, England, color manufacturer, have invented an Improved Process of Ornamenting Wall and Other Papers; and I do hereby declare that the following is a full, clear, and exact description of the invention, which will enable others skilled in the art to which it appertains to make and use the same.

My invention relates to an improved process of producing a finish upon previously-printed wall and other papers in imitation of silk, satin, horse-hair, or other fabrics.

Whatever the nature of the finish or design to be produced or the kind of fabric to be finished or ornamented, the process consists in first coating the previously-printed fabric with a varnish or compound of nitro-cellulose, and then embossing or frictioning and embossing (according to the kind of finish desired) the varnished or coated surface.

The varnish or coating consists, essentially, of nitro cellulose dissolved in acetate of amyl or in acetate of amyl and amylic alcohol, with or without the addition of castor or linseed oil, as specified in two other applications for Letters Patent, respectively dated July 24, 1885, Serial No. 138,706, and May 9, 1885, Serial No. 164,973.

In order to produce a silk, satin, or horse-hair-cloth finish on wall or other papers, the paper is first coated with the said varnish, and when the same is dry it is passed through an embossing machine, the rollers of which are suitably engraved to produce the desired effect, the rollers being preferably heated and running either at unequal or equal speeds, according as it is or is not desired to produce a frictioning as well as an embossing action to produce the desired effect; or the paper after being varnished might before being embossed be passed through a friction-calender.

I am aware that wall-papers have heretofore been embossed, and they have also been varnished; but the effect produced by my invention has never heretofore been obtained.

It will be understood from the foregoing that I coat finished or printed wall-paper, and that 50 said coating, being transparent, allows the printed matter to be clearly shown, and the coating is very thin and constitutes a mere varnish. This varnished and printed paper is embossed in any of the ways stated to give 55 the desired finish.

Heretofore plain paper—that is, unprinted paper or fabric—has been coated with parke-sine or xylonite, and the coating itself before becoming dry ornamented. The coating was 60 evidently opaque, so as not to show the plain fabric. I do not claim such as of my invention.

I claim—

1. The herein-described process of ornamenting wall-paper, which consists in coating the printed paper with a thin transparent varnish composed, essentially, of a solution of nitro-cellulose, and subsequently embossing the said varnished paper throughout its substance after the varnish has become dry, substantially as set forth.

2. The herein-described process of ornamenting wall-paper, which consists in first coating the printed paper with a transparent 75 varnish of nitro-cellulose solution, and then frictioning and embossing the said varnished paper throughout its substance after the varnish has become dry, substantially as set forth.

3. As an improved article of manufacture, a 80 web of printed wall-paper having its printed surface coated with a thin transparent varnish of nitro cellulose, the said varnish being embossed to present a silk, satin, or horse-hair finish, substantially as set forth.

Dated 21st day of May, 1885.

WILLIAM VIRGO WILSON.
